199,511

UNIT FOR DISPENSING LIQUID THERMOPLASTIC
MATERIAL AND FOR CHILLING MOLDS CON-
TAINING SAME

James B. McCormick, 521 S. Madison, La Grange, Ill.

Filed July 2, 1963, Ser. No. 75,620

Term of patent 14 years

(Cl. D83—12)

Fig 2

Fig 3

FIGURE 1 is a perspective view of the unit showing my new design;

FIGURE 2 is a top plan view of the unit; and

FIGURE 3 is a front elevational view of the unit.

The dominant features of the design reside in the portions shown in full lines. The textured areas in FIGURE 1 have been partially shown for convenience of illustration.

What is claimed is:

The ornamental design for a unit for dispensing liquid thermoplastic material and for chilling molds containing same, substantially as shown and described.
